COVER FOR A STORAGE BATTERY CASE

Andreas Karl Rohé, Konigstein, Taunus, Germany, assignor to Walter Glass, Northfield, Ill.

Filed June 21, 1963, Ser. No. 75,469

Term of patent 14 years

(Cl. D26—6)

FIG. 1 is a top plan view of a cover for a storage battery case, showing my new design;

FIG. 2 is a bottom plan view;

FIG. 3 is a side elevational view, the opposite side being substantially a mirror image thereof; and

FIG. 4 is a front elevational view, the rear being substantially a mirror image thereof.

I claim:

The ornamental design for a cover for a storage battery case, as shown and described.
